CATHODE SPOT CONTROL

Richard L. Longini, Pittsburgh, Pa., assignor to
Westinghouse Electric Corporation, East Pitts-
burgh, Pa., a corporation of Pennsylvania

Application August 19, 1948, Serial No. 45,010

4 Claims. (Cl. 250—27.5)

1

My invention relates to a vapor-electric device and particularly to an excitation arrangement for maintaining the cathode spot within a predetermined area on the liquid cathode.

In the operation of metal tank vapor-electric devices, it is necessary to prevent the attachment of the cathode spot to any portion of the metal container. Heretofore, this has been accomplished mainly by "brute force" methods at great expense and inconvenience. Usually the attachment of a cathode spot to the metallic container is prevented either by complicated shields or by insulating devices interposed between the cathode surface and the metallic container.

I have found that if a conductor is extended upwardly through the surface of the cathode pool adjacent to the desired position of the cathode spot, and the keep-alive electrode is placed in the vicinity of this vertical conductor and a current flows within the vertically-extending conductor (that is, a current flows in the conductor parallel to the keep-alive arc and in the reverse direction), a field will be established about the conductor which will draw the cathode spot into the vicinity of the conductor and prevents its wandering over the surface of the pool so that it might become attached to the metallic container.

It is an object of my invention to provide an excitation system having inherent means for restricting the motion of the cathode spot away from a predetermined surface area on the cathode pool.

It is a further object of my invention to provide means for restricting the cathode spot to a predetermined portion of a cathode pool.

It is a further object of my invention to provide an improved excitation system for a vapor-electric device.

It is a further object of my invention to provide a conductor for establishing a spot control field in a vapor-electric device.

Other objects and advantages of my invention will be apparent from the following detailed description taken in conjunction with the accompanying drawing in which the figure is an elevation partially in section of a vapor-electric device containing an excitation system according to my invention.

In the exemplary embodiment of my invention, the vapor-electric device has a metallic container 1 in which is a cathode 2 of vaporizable reconstructing material such as mercury, gallium, cesium, potassium or sodium. Cooperating with this cathode 2 is an anode 3 maintained in spaced insulated relation to the container 1 by means of 55

2

a suitable insulator 4, current being conducted to the anode 3 by means of a suitable lead-in connection 5.

The excitation system according to my invention comprises a make-alive electrode 10 or igniter having a resistance material in contact with a portion of the cathode material 2 and having suitable means such as an impulsing transformer 11 to produce impulses for initiating a cathode spot on the normally liquid cathode 2.

In order to maintain the cathode spot, a keep-alive electrode 12 of suitable material is placed above the cathode surface in the vicinity where it is desired to maintain the cathode spot. Also in the vicinity where it is desired to maintain the cathode spot is a vertically-extending conductor 13 preferably insulated from the cathode material by suitable high-temperature insulators 14.

When a single keep-alive electrode 12 is utilized, it is usually desirable to impress a substantially direct-current, keep-alive potential on the keep-alive electrode 10. Also, it is desirable to maintain a substantially uni-directional current in the vertically-extending conductor 13.

The current connection to the keep-alive electrode 12 may be completely separate and distinct from the conductor 13 and such connections may be at times most desirable. When separate supply connections are provided for the keep-alive electrode 12 and for the conductor 13, the current in the upward direction in the conductor 13 is adjusted to attract the cathode spot into the vicinity of the conductor 13.

I have found very satisfactory results may be obtained by mounting the keep-alive electrode 12 on the vertical conductor 13 and providing means for maintaining two substantially independent currents in the vertical conductor 13.

I prefer to maintain these separate currents by providing current-limiting means 18 in the return connection 16 from the keep-alive electrode 12 and in a return connection 17 from the vertically-extending conductor 13. Preferably, these current-limiting devices 18 are impedances connected in series with the various currents.

As a specific example of a supply system, I have shown a transformer 20 energized from an alternating-current source (not shown), supplying potential through a full-wave rectifying device 21, the positive connection 22 of which is connected to the vertically-extending conductor 13. Mounted on this conductor 13 is the keep-alive electrode 12 and also connected to this conductor is a separate return connection 17.

The currents flowing in the keep-alive circuit

16 and the return circuit 17 are adjusted by the impedances 18. The current flowing up to the keep-alive electrode 12 and the current flowing up to the return circuit 17 both assist in forming the magnetic field to attract the cathode spot so that the total power consumption is reduced, in some instances, by combining the keep-alive and attracting currents in the conductor 13. In practice, the keep-alive current is adjusted to maintain a single cathode spot and the current in conductor 13 is adjusted to attract the spot closely in the vicinity of the conductor 13. Since the cathode spot is found to move in a direction reverse to the direction in which a conductor would tend to move, it is believed that currents above that necessary to attract the cathode spot should be avoided. Also supplied from the source of alternating current is an impulsive transformer 24 for supplying impulses to the make-alive electrode 10.

When putting this system into operation, the impulsive transformer 24 will cause the initiation of a cathode spot by passing an impulse through the make-alive electrode 10. The keep-alive electrode 12 then picks up the cathode spot and causes current to flow through the relay 25 which opens the connection of the impulsive transformer 24 and maintains it out of action so long as the keep-alive electrode 12 is activated. In the event the keep-alive arc should go out, the relay 25 then will close, energizing the impulsive transformer 24 and re-initiating the cathode spot.

In order to maintain a cathode spot in a desired region adjacent to the vertically-extending conductor 13, a current must travel in the upward direction through the vertically-extending conductor 13 in excess of the current flowing through the keep-alive electrode 12. In practice the impedances 18 are adjusted so that the proper proportion of current flows to maintain the cathode spot, and also current flows upwardly through the vertically-extending conductor 13 to increase the magnetic field which draws the cathode spot into the immediate vicinity of the upwardly-extending conductor 13.

In practice, I have found that an independent or controlled current of the order of 20 to 30 amperes in the vertically-extending conductor 13 was ample to maintain the cathode spot within the desired region. When the current became too small, there was a tendency for the cathode spot to wander out of control distance and frequently to extend into the region of the metallic container 1, while currents greater than 30 amperes were apparently of no material advantage.

While for purpose of illustration I have shown a preferred embodiment of my invention and described my invention to the best of my present understanding, I wish it to be understood that I am not limited to the example or explanations herein given, and it is apparent that many changes and modifications can be made herein

without departing from the true spirit of my invention or the scope of the appended claims.

I claim as my invention:

1. In a vapor-electric device having a main anode and a pool-type cathode, an exciting system comprising a make-alive electrode, impulsive means for applying potential impulses to said make-alive electrode for initiating an electron emitting spot on said cathode, a keep-alive electrode, circuit means for applying potential to said keep-alive electrode for maintaining said electron emitting spot, a conductor extending upward through said pool adjacent said keep-alive electrode and circuit means for causing current flow in said conductor upward from said pool for anchoring said electron emitting spot adjacent said conductor.
2. In a vapor-electric device having a liquid cathode, a spot fixing system comprising a keep-alive electrode positioned adjacent the desired location of the cathode spot, a conductor extending through the cathode at the desired location of the cathode spot, a cathode spot initiating electrode adjacent the desired location of the cathode spot, a circuit for delivering cathode spot initiating potential to said cathode spot initiating electrode, a source of unidirectional current connected to said keep-alive electrode to maintain a keep-alive arc between said keep-alive electrode and said cathode and circuit means for producing an upwardly directed current in said conductor in excess of the current flowing in said keep-alive arc.
3. An exciting system for a vapor-electric device having a main anode and cathode comprising an electrode for initiating an electron emitting condition on said cathode, a second electrode for maintaining said electron emitting condition, connections for impressing a potential impulse on said first electrode, a source of substantially constant potential connected to said second electrode, a conductor extending through the cathode in the vicinity of the second electrode, circuit means for causing a current to flow in said conductor independent of the current for maintaining the emitting condition of said cathode.
4. In a vapor-electric device having a vaporizable cathode, a conductor extending through said cathode at a predetermined position therein, a keep-alive electrode spaced from the surface of the cathode in the immediate vicinity of said conductor, a source of unidirectional potential and connections for maintaining an exciting arc between said cathode and said keep-alive electrode and connections for maintaining a current in said conductor, said current having a direction opposite to and of greater magnitude than the keep-alive arc current.
